CLAIM

The ornamental design for a combined floor lamp with controller therefor, as shown and described.

DESCRIPTION

FIG. 1 is a front view of a combined floor lamp with controller therefor, showing our new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof; and

FIG. 8 is a back perspective view thereof.

FIG. 9 is another back perspective view thereof, showing the floor lamp and the controller separated;

FIG. 10 is a front view of the floor lamp in the combined floor lamp with controller therefor, showing our new design;

FIG. 11 is a back view thereof;

FIG. 12 is a left side view thereof;

FIG. 13 is a right side view thereof;

FIG. 14 is a top view thereof;

FIG. 15 is a bottom view thereof;

FIG. 16 is a front perspective view thereof; and,

FIG. 17 is a back perspective view thereof.

The broken lines in the figures show portions of the combined floor lamp with controller therefor that form no part of the claimed design. The shade lines in the figures are utilized to illustrate surface contours of the claimed design and do not depict surface ornamentation.

1 Claim, 17 Drawing Sheets
